UNITED STATES PATENT OFFICE.

ARTHUR DOHmen, OF COLOGNE, GERMANY.

APPARATUS FOR THE ELECTROLYTIC DECOMPOSITION OF WATER.

1,211,687.

Specification of Letters Patent.

Patented Jan. 9, 1917.

Application filed October 20, 1913. Serial No. 796,258.

To all whom it may concern:

Be it known that I, ARTHUR DOHmen, a citizen of the German Empire, and resident of Cologne-on-the-Rhine, Germany, have invented certain new and useful Improvements in Apparatus for the Electrolytic Decomposition of Water; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The electrolytic production of oxygen and hydrogen by the decomposition of water is carried out chiefly in apparatus that has the form of a filter press. The advantage of this form of apparatus as compared with the so-called "bell-apparatus" is that it occupies much less space.

The filter-press decomposing batteries have heretofore included an assemblage of cast iron electrodes and their cast iron frames. The dimensions and weight of these cast iron electrodes and frames were limited by the nature of the material, and it has been a problem to devise some construction that will cheapen the cost of installation, increase the efficiency, and decrease the erection or installation costs. By using wrought iron I have been able to accomplish these ends; thus obtaining thinner sections which have a degree of flexibility far exceeding that of cast iron, so that when drawing the sections together under heavy pressure the breakage of the sections has been almost entirely eliminated. By reason of the reduced quantity of iron in the sections less energy is unproductively absorbed in heating them up to the proper electrolyzing temperature, about 50°-60° C. Another important feature is that the corrugated sheet metal electrodes can be given greater area by reason of the corrugations than can be given cast iron, and I also provide in the top side of each frame a separating chamber for each gas, so that the gas will separate therein before passing to the gas conduits. Into these chambers the rising bubbles of gas carry the foam or froth and separate therefrom, the separated liquid settling back into the cell while the gases pass off through the conduits substantially free from entrained electrolyte. This has overcome a very serious

objection, as heretofore no separating chamber has been provided at the cells and the consequence has been a difference of level in the electrolyte on opposite sides of the porous diaphragms, due to back pressure, and a diffusion or passage of the hydrogen into the oxygen, so that impure oxygen was obtained. By my construction the liquid level on both sides of the diaphragms remains the same, there being no back pressure, so that I am enabled to obtain pure products.

Referring to the drawings, in which like parts are similarly designated—Figure 1 shows a frame bearing electrode embodying my invention. Fig. 2 is a vertical section taken through the right hand gas conduit 5. Fig. 3 is a horizontal section through the electrode. Fig. 4 is a horizontal section of a diaphragm. Fig. 5 is a vertical section through a battery of assembled cells, and Fig. 6 is a section on line 5—6 of Fig. 5.

The top side of a suitably shaped frame, for example, a quadrilateral frame 1 is provided with two gas chambers, one 3, on one side of the electrode 2, and the other 4, on the other side of the electrode. This electrode 2 is made of a separate piece of metal and is suitably secured to the frame 1 by a welding operation, or otherwise, as desired. Thus, the electrode, being detachable, may be readily renewed without renewing the frame. These chambers are located toward opposite ends of the top side of the frame, and communicate with their respective passages or conduits 5 and 6. The froth or foam produced by the rising bubbles of gas enters these chambers, and the gas separates therefrom, passing to the conduits, while the liquid settles back into the body of the electrolyte, so that comparatively little or no froth is carried along the gas mains.

The consecutive gas chambers of the same kind of the entire battery are connected by the passages, 5 or 6, to the same gas main. These passages also register with corresponding passages in the diaphragm which is clamped between two adjacent frames 1 and insulated therefrom. The diaphragms consist of a sheet of metal, 7, of the same size as the frames 1, having the interior cut away, as shown at 10, Fig. 4. To one side of the sheet are secured a number of spaced, preferably vertical, strips 8 of suitable material, as metal, and to the other side of the sheet are secured like spaced strips 9, opposite the spaces between the strips 8, as more clearly

shown in Figs. 4 and 6. Between each electrode frame 1 and each diaphragm 7 is secured, in any suitable way, an insulating frame or gasket 11, which is of sufficient thickness to keep the frames and diaphragms in spaced relation with each other. This arrangement completely insulates the diaphragms and electrodes. Such diaphragms when made of metal can well be used and remain neutral when the current remains about three volts and has a density of about two amperes per square decimeter or less. Consequently the electrolyte can circulate through the diaphragms without carrying the liberated gases along with it, and especially if the cells be kept full of electrolyte at the same level.

In lieu of the strips 8 and 9 I may use a fine wire mesh, or may insert such a mesh between the two series of strips 8 and 9 within the opening 10.

I claim:

1. In a series of cells of the filter-press type, a cell member having a quadrilateral straight edged frame, separate passages below the upper edge of the frame and gas separating chambers formed in the top of the frame each communicating with a passage.

2. In a series of cells of the filter press type, a cell member having a quadrilateral straight edged frame, two passages below the upper edge of the frame, a gas separating chamber formed at one end of said top in one side thereof and a second chamber formed at the other end of said top in the other side thereof, each chamber communicating with a passage.

3. In a series of cells of the filter press type, a cell member comprising a wrought iron frame having gas passages below the upper edge thereof and a detachable electrode.

4. In a series of cells of the filter press type, a cell member comprising a thin polygonal wrought iron frame, an electrode detachably secured thereto, two gas passages therethrough one of which conducts gas from one side of the electrode and the other conducts gas from the other side of the electrode.

5. In a series of cells of the filter press type, a cell member comprising a quadrilateral frame containing a single central opening and two passages through the top

of said frame, a sheet metal electrode secured to the frame within said opening and two gas separating chambers in the top of said frame, one at one side of the electrode and communicating with one of said passages, and the other at the other side of said electrode communicating with the other passage, said chambers extending from said passages laterally and downward to the active faces of the electrode.

6. In a series of cells of the filter press type, a cell member comprising a frame and a bi-polar sheet metal electrode in said frame, in combination with a metallic diaphragm adjacent said electrode and having passages through it over its entire surface and opposite the active faces of the electrode for the circulation of the electrolyte.

7. In a series of cells of the filter press type, a cell member comprising a flexible metallic frame and a bi-polar electrode in said frame; in combination with a metallic diaphragm adjacent said electrode having slots therethrough distributed over its entire surface and opposite the active face of said electrode.

8. In a series of cells of the filter press type, a cell member comprising a flexible wrought iron frame having a central opening and a thin, flexible, corrugated sheet-metal electrode secured within the opening, whereby both frame and electrode will simultaneously bend under assembling strains in the series of cells.

9. A diaphragm consisting of a sheet metal plate having an opening thereon, and spaced metal strips secured to the plate on opposite sides thereof extending across the opening, the strips on one side being opposite the spaces between the strips on the other side of the plate.

10. A diaphragm consisting of a sheet metal plate having an opening therein, and spaced vertical metal strips secured to the plate on opposite sides thereof extending across the opening, the strips on one side of the plate being opposite the spaces between the strips on the other side.

In testimony that I claim the foregoing as my invention, I have signed my name in presence of two subscribing witnesses.

ARTHUR DOHmen.
